UNITED STATES PATENT OFFICE.

GEORGE R. ALLISON, OF INDIANOLA, IOWA.

GUARD FOR DISK HARROWS.

971,874.

Specification of Letters Patent. Patented Oct. 4, 1910.

Application filed January 26, 1910. Serial No. 540,692.

To all whom it may concern:

Be it known that I, GEORGE R. ALLISON, a citizen of the United States of America, and resident of Indianola, Warren county, 5 Iowa, have invented a new and useful Guard for Disk Harrows, of which the following is a specification.

The object of this invention is to provide a guard for disk harrows.

10 My invention consists in the construction, combination and arrangement of elements hereinafter set forth, pointed out in my claims and illustrated by the accompanying drawing, in which—

15 Figure 1 is a plan of a disk harrow provided with my improved guard. Fig. 2 is a rear elevation of the same.

In the construction of the device as shown the numerals 10, 11 designate axles, each 20 carrying a plurality of disks 12. Bearings 13, 14 are mounted on the axles 10, 11 respectively, and the said axles are revoluble therein. Posts 15, 16 are fixed to and rise from the bearings 13, 14 respectively, and 25 extend above the frame bars 17, 18 of the machine. Bearings 19, 20 are mounted on the axles 10, 11 and the said axles are revoluble therein. Upright bars 21, 22 are fixed to and rise from the bearings 19, 20 30 respectively, and said upright bars support and carry the frame bars 17, 18 of the machine. Guard bars 23, 24 are fixed to the posts 15, 16 by means of flanges on the end portions of said bars 23, 24, and said bars 35 extend forward from the posts 15, 16, in converging planes, and are bolted to the tongue 25 of the machine. Guard bars 26, 27 are bolted to the posts 15, 16 adjacent to the tops of said posts, by means of twisted 40 portions 28, 29 on said guard bars. The guard bars 26, 27 extend forward and downward from the tops of the posts 15, 16, in converging planes, and are bolted to the tongue 25 through feet 30, 31 on the ends 45 of said guard bars. Brace bars 32, 33, of

common form, are fixed to the bearings 13, 14 and extend forward therefrom in converging planes and are bolted to the tongue 25. A seat 34 is mounted on the frame bars 17, 18 between the guard bars 23 and 24 50 and also between the guard bars 26 and 27.

In use the operator takes his position on the seat 34 and operates the machine in the usual manner. The guard bars 23, 24 and 55 26, 27 extend beneath, to the sides, and in front of the driver and prevent his falling or being pulled to the ground in front of the disks 12 to his consequent and perhaps very serious injury.

I claim as my invention—

1. A guard for disk harrows, comprising 60 bearings mounted on the axles of said harrow, posts fixed to and rising from said bearings, and guard bars fixed to said posts at one end and extending forward in converging planes and fixed at their other ends to the tongue of said harrow in front of the driver's seat.

2. A guard for disk harrows, comprising 65 bearings loosely mounted on the axles of said harrow, posts fixed to and rising from said bearings on either side of the driver's seat of said harrow, guard bars fixed to said posts at different vertical points and extending forward and fixed at their other 70 ends to the tongue of said harrow.

3. The combination of a disk harrow and 75 a guard comprising posts fixed to and rising from bearings on the axles of said harrow, and guard bars fixed at one end to said posts, extending forward therefrom on opposite sides of the seat of said harrow, and fixed at their other ends to the tongue of said harrow in front of said seat.

Signed by me at Indianola, Iowa, this 80 26th day of July, 1909.

GEORGE R. ALLISON.
